INSULATING STRUCTURES

David W. Evans, Erie, Pa., assignor to General Electric Company, a corporation of New York

Application July 9, 1952, Serial No. 297,959

6 Claims. (Cl. 312—214)

My invention relates to refrigerator cabinets and the like, and more particularly to insulating structures therefor.

In some cabinets, such as refrigerator cabinets and the like, where a temperature differing substantially from that of the surrounding atmosphere is to be maintained, insulation including an evacuated sealed envelope may be employed. This insulation may be, for example, in the form of an evacuated metal envelope including a glass fiber filler, such as that described and claimed in the copending application of Herbert M. Strong and Francis P. Bundy, Serial No. 236,788, filed July 14, 1951, and assigned to the same assignee as the present invention. It is to be understood that my invention is an improvement over the invention of the Strong and Bundy application, and therefore, I do not claim as my invention anything shown or described in said Strong and Bundy application, which is to be regarded as prior art with respect to the present application. Insulation such as that described and claimed in the Strong and Bundy application has excellent thermal insulating properties, representing a substantial improvement in this respect over conventional or standard insulation, for example, atmospheric glass fiber batts, i. e., glass fiber batts under atmospheric conditions, used in many present-day refrigerators. Such vacuum panels may conveniently be employed between the inner and outer walls of conventional refrigerators in lieu of the standard insulation. When so employed, they make possible a substantial reduction in the thickness of the walls, thereby materially increasing the available interior storage space for the same exterior dimensions. However, insulation of this type, because of the sealed envelope which is employed, has introduced the problem of heat leakage from one wall of the panel to the other along the edges thereof. By my invention, a combined insulating structure is provided which minimizes the effect of such edge leakage and secures an overall improved cabinet insulating structure.

It is an object of my invention to provide an improved insulating structure for cabinets and the like.

It is another object of my invention to provide an improved insulating structure for doors utilized as parts of such cabinets.

It is a further object of my invention to provide an improved arrangement for reducing edge losses of sealed evacuated, insulating panels.

Further objects and advantages of my invention will become apparent as the following description proceeds, and the features of novelty which characterizes my invention will be pointed out with particularity in the claims annexed to and forming part of this specification.

In carrying out the objects of my invention, vacuum panels including sealed envelopes are employed in the two side walls and the top wall of the cabinet, and in the door. The top corners of the cabinet are formed to provide a space for receiving atmospheric insulation to provide a long thermal path and to reduce heat losses at the edges of the panels. Atmospheric insulation is used

2

in the back wall and in the bottom wall of the cabinet. The door is shaped to provide a portion of increased thickness along the perimeter thereof, and atmospheric insulation is placed in this portion of increased thickness adjacent the edges of the vacuum panel to minimize heat loss at the edges.

For a better understanding of my invention, reference may be had to the accompanying drawings, in which Fig. 1 is a front elevation view, partly in section, of a refrigerator cabinet incorporating an embodiment of my invention; Fig. 2 is an enlarged sectional plan view taken along the line 2—2 in Fig. 1 and looking in the direction of the arrows; Fig. 3 is a sectional plan view of a portion of a door showing a modified form of my invention; and Fig. 4 is a view similar to Fig. 3 showing another modified form of my invention.

Referring to Figs. 1 and 2, there is shown a refrigerator cabinet 1 including an outer wall or shell 2 and an inner wall or liner 3 spaced from the outer wall and defining a food storage compartment 4. A machinery compartment 5 is provided below the food storage compartment. The access opening of the food storage compartment is closed by a door 6 and the access opening of the machinery compartment 5 is closed by a cover 7. The space between the outer and inner walls 2 and 3, respectively, at the access opening is closed by a breaker strip 7a of a material of low thermal conductivity, such as any of several plastic materials now generally employed. The breaker strip may be held in position by screws, one of which is shown at 7b, engaging a nut strip 7c on the inner liner 3. The particular mounting of the breaker strip with one end overlapping an inturned flange of the outer wall and with a screw engaging the inner wall is not part of my invention but, in connection with the mounting of a gasket, is described and claimed in the copending application of Leroy R. Patterson, Jr., Serial No. 321,368 filed November 19, 1952, now Patent No. 2,704,698; granted March 22, 1955, and assigned to the same assignee as the present application.

The food storage compartment 4 is cooled by refrigerating apparatus (not shown) so that a substantial difference in temperature normally exists between the temperature within the compartment 4 and the temperature of the atmosphere surrounding the cabinet 1. To assist in maintaining this temperature differential, the space between the outer wall 2 and the inner liner 3 is provided with thermal insulating material. In the structure illustrated, a plurality of vacuum panels 8 and 9 are employed in the side and top walls respectively of the cabinet. While in the structure illustrated in Fig. 1 only the vacuum panel 8 in the left-hand side wall has been shown, it will be understood that the same construction is employed in the right-hand side wall which is not shown in section. Each panel may be placed between the outer and inner walls 2 and 3 in any suitable manner. By way of example, in the form illustrated, a plurality of spaced strips or spacer members 10, which may be simply strips of cardboard, are employed between the walls of the panel and the inner and outer walls of the cabinet, so as to permit some relative movement of the panel and the walls. It will be apparent, however, that these spacer strips could be omitted if desired.

Each of the panels 8 and 9 may be made in accordance with the invention disclosed in the aforementioned Strong and Bundy application. Each panel thus includes two sheets or members 11 and 12. By way of example, the member 11 may be a flat sheet and the member 12 may be a pan-shaped sheet, providing a space between the members 11 and 12. Since the panel envelope must be perfectly sealed against leakage in order to maintain the necessary vacuum in the panel, the walls 11 and 12 are conveniently formed of some suitable metal, such as steel.

The space between the members 11 and 12 is filled with a particular glass fiber insulation 13 in accordance with the teaching of the aforementioned Strong and Bundy application, and the adjacent edges 14 of the members 11 and 12 are welded to seal the envelope. The enclosed space is evacuated to very low pressure, resulting in an insulation having greatly improved thermal insulating properties. Because of these improved insulating properties, a much thinner wall of insulation may be employed than in the case of present conventional insulation, thereby greatly reducing the thickness of the cabinet walls and substantially increasing the available food storage space within the cabinet.

While such panels provide substantial thermal resistance to heat flow between the sheets 11 and 12 throughout almost the entire area of the panel, this substantial resistance does not exist at the edges of the panels because in these regions the envelope members 11 and 12 provide for conduction of heat directly from one wall of the panel to the other. This heat conduction is particularly significant where the sheets 11 and 12 are formed of a metal such as steel which is a good conductor of heat. However, in any event, the heat conduction will be greater through the material of the sheets 11 and 12 at the edges, for example, through the path at A, than through the evacuated structure forming the remaining area of the panel, for example, through the path B. This introduces the problem of heat leakage at the perimeter of each of the panels, with resulting warm areas in these regions of the storage compartment and condensation or sweating on the exterior of the cabinet in these regions. By my invention the adverse effects of such edge losses in vacuum panels are materially reduced.

Referring to Fig. 1, the upper corners of the liner 3 are inclined or chamfered, as indicated at 15, providing an increased distance between the edges of the panels and the inner liner in these regions. While only a portion has been shown in Fig. 1, it will be understood that the inclined section 15 could, if desired, extend around the entire perimeter of the top wall of the liner. The space between the inclined section 15 and the adjacent edges of the panels 8 and 9 is filled with atmospheric insulation, for example, glass fiber insulation. This insulation, indicated at 16, fills the space between the section 15 and the edges of the panel and also surrounds and encloses the edges of the panels, as indicated at 17, for example.

It can be seen by reference to Fig. 1 that with this construction a substantially longer heat flow path is provided at the inclined section 15 and the thickness of atmospheric insulation thus made available is sufficient to give substantially the same resistance to heat flow between the outer and inner walls 2 and 3 in this region as is provided by the smaller thickness of insulation afforded by the vacuum panel in the remainder of the top and side walls of the cabinet.

While vacuum panels could, if desired, also be employed in the rear wall of the refrigerator cabinet, I prefer to employ a batt 18 of atmospheric insulation, such as the glass fiber insulation employed at 16, in the space between the rear wall 19 of the outer wall 2 and the rear wall 20 of the inner liner 3. As a practical matter, the exterior depth of the refrigerator cabinet is determined by the standard depth of other kitchen appliances and cabinets. The interior depth is also somewhat limited because if this depth becomes too great, the difficulty of access to items stored in the rear of the food storage compartment 4 becomes significant. Also, in many refrigerators it is customary to install the evaporator through an opening in the rear wall, and making the insulation of the rear wall of a sealed vacuum panel would introduce some difficulties in connection with the assembly of the evaporator. Accordingly, in the refrigerator cabinet herein disclosed, atmospheric rather than vacuum panel insulation is employed in the rear wall of the cabinet. The use of this standard insulation and hence the

much greater thickness thereof employed increases the distance between the edge 14 of the panel as shown in Fig. 2 and the closest point 21 of the liner over that which would exist were the thinner vacuum panel also to be employed in the rear wall. The arrangement illustrated in Fig. 2 thus provides for an increased length of heat path from the edge of the panel and hence minimizes the adverse effect of edge losses through the metal envelope of the panel, as discussed above. It will be apparent that alternatively, if a vacuum panel were employed in the rear wall of the cabinet, the corners of the liner at the junctions between the rear and side walls thereof could be chamfered in the same manner as corner 15 previously described, and the corner of the liner at the junction of the rear and top wall of the liner could, as mentioned above, be chamfered in the same manner as the corner 15.

Vacuum panel insulation also could be employed, if desired, in the bottom wall of the cabinet, i. e., in the wall between the food storage compartment and the machinery compartment 5. In accordance with the form illustrated, however, a batt 22 of atmospheric insulation similar to the batt 18 described above, is also employed in this bottom wall. This batt, like the batt 18, being of substantially greater thickness than the vacuum panel, provides an increased length of heat flow path from the edge 14 and hence from the outer metal wall 12 of the panel to the adjacent corner 23 of the liner.

A vacuum panel 24 is also provided to insulate the door 6. The door includes an outer metal wall 25 and an inner metal wall 26 connected by a breaker strip 27 of suitable thermal insulating material, such as one of the plastic materials currently employed for this purpose. The breaker strip may be secured to the inner wall 26 by screws, one of which is shown at 28. The vacuum panel 24 is spaced from the outer and inner walls 25 and 26 by spacers 29, which may be cardboard strips. The panel 24 is made in the same manner as the panel 8 described above and includes two sheets or members 30 and 31, sealed at their abutting edges 32. As in the case of the panel 8 one sheet 30 may be pan-shaped and the other sheet 31 may be flat. The space between the members 30, 31 is filled with the particular glass fiber insulation 33 disclosed in the aforementioned Strong and Bundy application. The use of this improved insulation provided by the vacuum panel makes possible a substantial reduction in the thickness of the door. However, the edge loss problem discussed in connection with the cabinet structure above is also present in the door structure employing the vacuum panel, i. e., the heat loss in the region 34 between the outer member or sheet and the inner member or sheet of the panel. In accordance with my invention, the effect of this heat loss is minimized by substantially increasing the thickness of the door in the region of the perimeter thereof. Thus, the door in the region 35 is made of substantially greater thickness than the remainder of the door area. The inner wall 26 of the door is drawn into a pan-shape, as indicated at 36, to provide for this greater thickness adjacent the perimeter. This shape of the inner wall of the door is advantageous in that it provides a space for mounting door shelves without having the shelves project material beyond the inner face of the door. The space 35 is filled with atmospheric insulation, for example glass fiber insulation such as that employed at 16, this atmospheric insulation also surrounding the edge of the vacuum panel 24 in the region 34 and providing a substantially increased heat flow path over that which would be available were the thickness of the door not increased at the perimeter thereof. Because of the substantially increased thickness, the insulating value of the atmospheric insulation employed can be made substantially the same as that of the much thinner vacuum panel is employed for insulation throughout the remainder of the door, and this thicker insulation in the particular region

employed minimizes the effect of edge losses between the metal sheets or walls of the panel. Hence, the possibility of a warm area within the food storage compartment in this region and the possibility of water condensation or sweating on the exterior of the door in this region is minimized.

In Fig. 3, there is shown a modified form of door structure which incorporates the same general insulating structure. The same numerals have been employed to designate corresponding parts in Figs. 2 and 3. Referring to Fig. 3, there is shown a door structure including an outer wall 25, a vacuum panel 24, and a plurality of spacers 29 for spacing the vacuum panel from the outer wall 25 and the inner wall 37 of the door. This form of door differs from that shown in Fig. 2 in that the entire inner wall 37 is formed of a suitable material of low thermal conductivity, for example, polystyrene or other suitable plastic material in lieu of the combined metal inner wall 26 and breaker strip 27 disclosed in Fig. 2. The inner wall 37 is molded to the same general shape as the combined metal inner wall and breaker strip 27, 28 of Fig. 2 providing a recessed portion 38, suitable for the reception of door shelves and the thicker portion 35 at the perimeter of the door. The region 35 is filled with the atmospheric insulating material, such as the glass fiber insulating material employed in Fig. 2.

Another form of door structure incorporating a combined vacuum panel and atmospheric thermal insulation is shown in Fig. 4. The form of the door shown in Fig. 4 also includes an outer wall 25, a vacuum panel 24, and spacers 29. The inner wall of the door includes a pan-shaped metal portion 39 which is coated with porcelain enamel and is shaped to provide a recessed portion for door shelves and to provide a thicker portion of door structure at the perimeter of the door. In this form of door structure, corner braces, one of which is shown at 40, are secured to the inner face 41 of the outer wall 25 of the door. A combined inner wall assembly including the metal wall 39 and a breaker strip section 42, which may be of any suitable material such as polystyrene or other plastic material, is secured by screws, one of which is shown at 43, to the corner braces. Blocks or spacers, one of which is shown at 44, of a material of low thermal conductivity are interposed between the combined inner wall assembly and the corner braces 40. The breaker strip section 42 is of U-shaped cross-section including a base portion 45 and two legs 46 and 47. The base portion 45 is arranged in line with a peripheral portion 48 of the inner wall 39 which extends inwardly from the central portion 49 of the inner wall 39. As in the forms disclosed in Figs. 2 and 3, the thicker portion of the door at the perimeter thereof, as indicated at 35, is filled with atmospheric insulation, such as glass fiber insulation, and this insulation surrounds the edge of the panel and reduces the edge losses.

While I have shown and described specific embodiment of my invention, I do not desire my invention to be limited to the particular constructions shown and described, and I intend, by the appended claims, to cover all modifications within the spirit and scope of my invention.

What I claim as new and desire to secure by Letters Patent of the United States is:

1. In a cabinet or the like including an outer shell and a spaced inner liner each shaped to provide a side wall and a rear wall, an insulating panel disposed in said side wall between said outer shell and said inner liner, said panel including two spaced sheet members sealed at their edges, the space between said members being evacuated, and a batt of atmospheric insulation of a thickness substantially greater than said panel, said batt being disposed in the back wall of said cabinet between said outer shell and said inner liner and extending adjacent to and overlapping an edge of said panel for

minimizing heat leakage between said outer shell and said inner liner at said edge.

2. In a cabinet or the like including an outer shell and a spaced inner liner each shaped to define a top wall and a side wall, a first insulating panel disposed in said side wall between said outer shell and said inner liner, a second insulating panel disposed in said top wall between said outer shell and said inner liner, each of said panels including two spaced sheet members sealed at their edges, the space between said members being evacuated, said inner liner including an inclined portion at the corner thereof joining said top wall and side wall thereof to provide a greater distance between said outer shell and said inner liner in this region, and atmospheric insulation disposed between said outer shell and said inner liner at said corner, said insulation being between and overlapping the adjacent edges of said first and second panels for minimizing heat leakage between said outer shell and said inner liner at said edges.

3. In a cabinet or the like including an outer shell and a spaced inner liner each shaped to define a top wall and two side walls, a first insulating panel disposed in one of said side walls between said outer shell and said inner liner, a second insulating panel disposed in said top wall between said outer shell and said inner liner, a third insulating panel disposed in the other of said side walls between said outer shell and said inner liner, each of said panels including two spaced sheet members sealed at their edges, the space between said members being evacuated, said inner liner including inclined portions at the junction between the top wall thereof and the side walls thereof to provide a greater distance between said outer shell and said inner liner in these regions, and atmospheric insulation disposed between said outer shell and said inner liner at said inclined portions, said insulation being between adjacent edges of said panels and overlapping said edges for minimizing heat leakage between said outer shell and said inner liner at said edges.

4. In a cabinet or the like including an outer shell and a spaced inner liner, each shaped to provide a side wall, a rear wall and a top wall, a first insulating panel disposed in said side wall between said outer shell and said inner liner, a second insulating panel disposed in said top wall between said outer shell and said inner liner, each of said panels including two spaced sheet members sealed at their edges, the space between said members being evacuated, said inner liner including an inclined portion at the corner thereof joining said top wall and said side wall thereof to provide a greater distance between said outer shell and said inner liner in this region, atmospheric insulation disposed between said outer shell and said inner liner at said corner, said insulation overlapping and extending between the adjacent edges of said first and second panels for minimizing heat leakage between said outer shell and said inner liner at said edges, and a batt of atmospheric insulation of a thickness substantially greater than that of said panels, said batt being disposed in the back wall of said cabinet between said outer shell and said inner liner and overlapping the adjacent edge of said panels for minimizing heat leakage between said outer wall and said inner liner at said edges.

5. In a cabinet or the like including an outer shell and a spaced inner liner, each shaped to provide two walls, a rear wall, a top wall and a bottom wall, a first insulating panel disposed in said side walls between said outer shell and said inner liner, a second insulating panel disposed in said top wall between said outer shell and said inner liner, each of said panels including two spaced sheet members sealed at their edges, the space between said members being evacuated, said inner liner including an inclined portion at the corner thereof joining said top wall and said side wall thereof to provide a greater distance between said outer shell and said inner liner in this region, atmospheric insulation disposed between said outer shell and said inner liner at said edges.

outer shell and said inner liner at said corners and between the adjacent edges of said first and second panels and overlapping said edges for minimizing heat leakage between said outer shell and said inner liner at said edges, a batt of atmospheric insulation of a thickness substantially greater than that of said panels, said batt being disposed in the back wall of said cabinet between said outer shell and said inner liner and overlapping adjacent corresponding edges of said panels for minimizing heat leakage between said outer walls and said inner liner at said edges, and a second batt of atmospheric insulation of a thickness substantially greater than that of said panels, said batt being disposed in the bottom wall of said cabinet between said outer shell and said inner liner and extending over the adjacent edge of said first panel for minimizing heat leakage between said outer wall and said inner liner at said edge.

6. In a cabinet or the like including an outer shell and a spaced inner liner, each shaped to provide two walls, a rear wall, a top wall and a bottom wall, a first insulating panel disposed in one of said side walls between said outer shell and said inner liner, a second insulating panel disposed in said top wall between said outer shell and said inner liner, a third insulating panel disposed in the other of said side walls between said outer shell and said inner liner, each of said panels including two spaced sheet members sealed at their edges, the space between said members being evacuated, said inner liner including an inclined portion at one corner thereof joining said top wall and said one of said side walls and a second inclined portion at the opposite corner thereof joining said top wall and said other of said side walls to provide a greater distance between said outer shell and said inner liner in these corner regions, the edges of adjacent panels extending into said corner

15
